UNITED STATES PATENT OFFICE.

JOHN F. A. HOORT, OF NEW YORK, N. Y., ASSIGNOR TO THE EAST ROCK-FORD MANTEL COMPANY, OF ROCKFORD, ILLINOIS.

DESIGN FOR A MANTEL.

SPECIFICATION forming part of Design No. 24,280, dated May 7, 1895.

Application filed April 4, 1895. Serial No. 544,496. Term of patent 3½ years.

To all whom it may concern:

Be it known that I, JOHN F. A. HOORT, a citizen of the United States, residing at New York, in the county of New York and State of New York have invented and produced a new and original Design for Mantels; and I do hereby declare the following to be a full, clear, and exact description of the same, reference being had to the accompanying drawing, forming a part thereof.

The figure of the accompanying drawing is an isometric view of the new design for mantels. Its leading feature consists in the design for a mantel comprising the mantel shelf 5 surmounted by a paneled frame having a cornice 15 supported at each end by two rectangular fluted columns each pair having a common base and a common capital the latter being beneath the frieze of an entablature whose 20 cornice surmounts the frame.

Numerals 1 denotes the mantel shelf and 2 supporting columns therefor. These stand upon pedestals 3 which also support mantel posts 4 in front of a skirt 6.

7 denotes a frame surmounting the shelf. 25 8 is a cornice for said frame which surmounts a frieze 9. 10 are capitals common to two columns 11 having fluted fronts. 12 denotes bracket like enlargements or sub-capitals provided with foliated ornamentation. 30

What I claim is—

The design for a mantel as herein shown and described.

In testimony whereof I affix my signature in presence of two witnesses.

JOHN F. A. HOORT.
